UNITED STATES PATENT OFFICE.

WALTER S. RYAN, OF NEW YORK, N. Y., ASSIGNOR TO LOUIS HENGERER, TRUSTEE, OF NEW YORK, N. Y.

ELECTRICAL MAKE-AND-BREAK-CIRCUIT DEVICE.

1,033,473:

Specification of Letters Patent. Patented July 23, 1912.

Application filed December 14, 1910. Serial No. 597,184.

To all whom it may concern:

Be it known that I, WALTER S. RYAN, a citizen of the United States, and a resident of the borough of Manhattan, city, county, 5 and State of New York, have invented a certain new and useful Improvement in Electrical Make-and-Break-Circuit Devices, of which the following is a specification, reference being had to the accompanying drawings, in which—

Figure 1 illustrates an elevation of a compact apparatus recently designed by me and which embodies the present invention; Fig. 2 illustrates a plan view of that which is 15 shown in Fig. 1; Fig. 3 illustrates an enlarged view in elevation of the parts immediately involved in the invention, showing one form in which they may be made and in which they are shown in the position they 20 occupy when the circuit is just about to be closed; Fig. 4 illustrates the position of the parts shown in Fig. 3, just after the brush has made contact and the circuit has been closed; Fig. 5 illustrates an elevation of a 25 desirable form of brush or contact bar.

In make and break circuit devices of the class here under consideration the conducting surfaces are usually worn away or disintegrated at the point of initial contact because of the burning action of the arc caused 30 by the relatively small area of such initial contact points, and also the illumination of the lamp is not instantaneously full and complete since ordinarily an appreciable 35 time intervenes between the moment of first contact and the time when a sufficient area of the brush is in contact with the conducting surface that co-acts with it, to transmit effectively the proper amount of current to 40 effect full and complete illumination.

My invention, therefore, supplies devices whereby the two conducting devices will be held apart free from contact until the mechanism in its orderly operation has brought 45 the parts into such position that being then allowed to make contact, the transmission of the current will be instantly full and complete, resulting in equally instantaneous, full and complete illumination of the lamp and 50 the formation of an arc will be wholly or partly avoided.

Referring now to the drawings, in which, as stated, I illustrate one form only of apparatus in which the invention may be employed, 1 represents a base of any suitable

material and of any preferred form; 2 a motor supported on the base; 3 a casing in the upper part of which a shaft 4 is properly journaled.

5 represents a pulley on the end of the 60 shaft, 6 another pulley on the motor shaft, and 7 a belt passing over both these pulleys. A worm on the shaft 4 engages with a worm wheel within the casing, whereby the shaft 8 on which the worm wheel is fixed, is turned. 65 These last named parts are not illustrated because their construction and method of operation are obvious.

Referring now to the devices which constitute the invention: 9, 9, are wheels mounted on the ends of the shaft 8 having segmental flanges 10 on parts of their peripheries. 11 are brushes clamped at their outer ends to suitable supporting surfaces 12 which may be any preferred part of the 75 structure. I prefer that the brushes should be made up of a series of plates or laminæ of suitable metal, (see Fig. 5) and that they be backed up by a somewhat thicker and more rigid plate 14 of phosphor bronze, and 80 that the several laminæ be rigidly bound together at their fixed end by an inclosing band or strap 15, but that the backing plate 14 be allowed to slide through the band 15, so that the clamping bolts 16 may rigidly hold all the parts composing the brush, yet the nuts being loosened, the plate 14 may be moved rearwardly to compensate from time to time for the wear of the brush. A strap 85 17 fastened to the plate 14, but not to the 90 other laminæ of the brush, incloses all the other laminæ and holds them in place. The front ends of the laminæ are cut off or shaped on the arc of a circle the same as that of the exterior of the conducting surfaces or flanges 10 of the wheels 9, so that 95 there shall be immediate and continuous contact throughout the entire area of these surfaces the moment they are brought together.

18 is what I call the arc preventer. It is, 100 or may be made in the form shown and of any suitable non-conducting material. I prefer porcelain. It is rigidly fastened to the front end of the conducting plates or flanges 10; but it may be otherwise supported. As 105 shown, it has a part 19 which extends radially beyond the plane of the conducting surface so that, as shown in Fig. 3, the free end of the brush will be pressed back, and, bent somewhat upward, and thus held away 110

from the part 10, during the rotation of the wheel, until all the laminæ of the brush are in position to drop simultaneously upon the part 10 when they finally escape from, or 5 pass beyond the part 19 of the arc preventer, as shown in Fig. 4, thus effecting contact between all the laminæ of the brush, or between all the contact surface of the brush, if 10 otherwise constructed, and the co-acting conducting part at the same moment of time, thus avoiding the formation of the destructive arc heretofore referred to.

My invention is more particularly useful in connection with electrical apparatus in 15 which the conducting surface or surfaces are segmental in form, that is to say, the moving part is broken away at appropriate places where it is desired to interrupt the current, so that the brush, when it reaches 20 the end of the part with which it makes contact, will drop away therefrom into an open space and the current will not be re-established until the front end of the next adjacent conducting segment makes contact 25 with the brush and in so doing first touches the brush at some distance from its end, because, owing to the elastic character of the brush, when it falls into the open space referred to, its end projects downwardly into 30 a different plane from that in which the conducting segment moves and if it were not for my insulating arc preventer located at the front end of the conducting surface, an arc will be formed each time the brush 35 makes contact therewith some distance, usually about an inch, back from the end of the brush and in time the first laminæ of the brush, if it be a laminated one, or if not, then the whole single thickness of the brush 40 will be disintegrated or burnt off, so that in time the brush end or the end of the first laminæ as the case may be will drop off and then in succession the succeeding laminæ will be burnt off and drop away 45 until finally the brush, instead of wearing away at its end in the normal manner, becomes much shortened by the destructive operation referred to and when this takes place, the arcing is greatly increased, resulting frequently in blistering and burning 50 of the segments or contact surfaces themselves. Furthermore the full length of the brush is necessary for its required resilient action to secure proper operation and if the 55 end of the brush is gone, its resilient action is largely and sometimes entirely wanting. Consequently it does not drop away from the rear end of the segmental or contacting surface as it should, on the contrary, it is 60 apt to remain in substantially the same plane as it, so that the arc created by the brush leaving the segmental surface is much

prolonged; resulting in burning away little by little not only the rear end of the conducting surface, but likewise more and more 65 of the brush, thus continually increasing the trouble, and sometimes if a new brush is not promptly supplied, serious injury, if not the destruction of the entire apparatus results.

Obviously the details of construction may be different from those illustrated. I show the contacting surfaces in the form of revolving wheels 9 having laterally projecting segmental surfaces 10, but any other 70 preferred construction having substantially the same parts in substantially the same relation to each other may be substituted therefor.

I claim:

1. In a make and break circuit apparatus, a driven shaft, a conducting member fast on the shaft and having laterally projecting segments, a brush adapted to engage with the projecting segments of the conducting 85 member and to drop into the open space in rear thereof, and non-conducting material secured to the forward end of each segment and projecting beyond the plane of the segment.

2. In a make and break circuit apparatus, a driven shaft, a conducting member fast on the shaft and provided with conducting segments, a resilient brush adapted to engage with the conducting segments of the 95 conducting member, and non-conducting material secured to the forward end of each conducting segment and projecting beyond the plane thereof, adapted to engage with the brush and press it away from the conducting segment until the non-conducting 100 material has passed.

3. In a make and break circuit apparatus, a driven shaft, a conducting member fast on the shaft and having laterally projecting 105 conducting segments, a resilient brush composed of a series of resilient laminæ, a backing plate for the brush laminæ, a strap supported by and fastened to the backing plate and which incloses the other laminæ of the 110 brush, the brush being so arranged as to engage with the projecting segments of the conducting member and to drop into the open space in rear thereof, and non-conducting material secured to the forward end of 115 each conducting segment in the path of the brush.

In testimony whereof I have signed my name to this specification in the presence of two subscribing witnesses.

WALTER S. RYAN.
